AUTOMATIC WORK-ADJUSTING C CLAMP

Anthony A. Wasilewski, Essex, Md.

Application September 27, 1943, Serial No. 503,964

1 Claim. (Cl. 144—304)

This invention relates to the type of clamps known as C clamps, and especially to such as have one or both jaws rotatably mounted, for instance, as in Patent No. 291,248, but is an improvement thereon in the respect presently explained.

One object of this invention is to provide a clamp that automatically operates to adjust the work-materials in a definite and exact relation to one another, in contradistinction to those clamps whose jaws are mounted to be swung in other than a single plane of rotation, as is the case where their mountings are other than cylindrical or conical. Therefore, I choose to name this invention an "Automatic work-adjusting C clamp."

In carrying this object into practice, I not only mount both jaws on cylindrical pivots, but I also provide plane jaw-seats on which the respective jaws are seated in proper relation to restrain them respectively from moving in any direction other than a single rotary movement around the respective cylindrical pivots or journals; and I also form the work-engaging face of each jaw with grooves that intersect one another at right angles and whose walls are in planes disposed at very obtuse angles to one another, viz., to the respective opposite surfaces, and which walls combine to form four work-engaging ridges that converge towards the pivot and are oblique to the axial line of the pivots and of the screw that moves one jaw towards the other.

Referring now to the accompanying drawing, in which, similar reference numerals refer to similar parts in the drawing and specification, the invention is now described as follows:

Fig. 1 is a view mainly in side elevation, but partly in section along the line I—I of Fig. 2, in connection with two units of work-material centered and clamped between the jaws.

Fig. 2 is a top plan view or face view of the work-engaging surface of the lower jaw shown in Fig. 1.

The C-shaped frame or body 3 has therein a screw-threaded opening 4 and has thereon a plane surface 5 as a seat for one of the jaws 6, this seat having a cylindrical opening 7 that serves as a bearing for a pivot 8 with which the jaw-seat 5 is provided for cooperation in restraining the jaw 6 from moving in any direction other than a true rotary direction. A hand-screw 9 has its thread operatively engaged with the internally threaded opening 4 so it is movable toward and from the seat 5 and jaw 6 and carries therewith a jaw 10 which is rotatable on a pivot 11

of the screw 9, and the latter has a plane surface 12 that cooperates with the pivot 11 to restrain this jaw 10 from moving in any direction other than a true rotary motion around its cylindrical pivot 11.

In the previously briefly described work-engaging face of each jaw, as shown in Fig. 2, the four work-engaging ridges are seen at the meeting edges of the walls 13, viz., at the respective lines 14 that cross one another at right angles at the axial line that is common to the pivots 8 and 11; and though these lines appear straight across in Fig. 2, there are actually four of such lines, or two pairs thereof, the lines of each pair being 15 at opposite sides of the line I—I and not only converging radially to the axis of the pivot 8, but also converging from the tops of the walls 13, at the periphery of the jaw, to the bottoms of these walls (at 15) and to the axial line of the pivots 8 and 11; in other words, these ridge-crests 14 are oblique to the axial line of the pivots 8 and 11, and they extend substantially from periphery to center of the jaw; but the ridge-crests 14a terminate at an opening 16 in which the riveted 20 end of the pivot 11 prevents displacement of the jaw 10.

In Fig. 1, a ball is seen at B, and a ring or length of tubing is seen at A, and as each of these have convex surfaces seated on or against the convergent ridge-crests of the respective jaws 10 and 6, they have not only been automatically centered with respect to these jaws and the axial line thereof, but are also restrained from becoming displaced in any direction because they have portions that are effectually surrounded by the ridge-crests 14 and 14a respectively; and being thus secured against displacement, they can be soldered or welded to one another without any danger of displacement during such operation; and the same would be true of two lengths of rod or tubing to be soldered, brazed or welded or otherwise secured together, whether in parallel relation or in crossed relation at any desired angle to one another; and in adjusting them to 30 the desired angle, either or both of the rotary jaws can be turned with the material engaged therewith while the centralized relation is undisturbed.

Because of the very obtuse angle between opposite pairs of the ridge-crests 14, and because of the extent of these ridges substantially from periphery to center, these jaws contact the tubing with only plane surfaces and at points widely spaced from the bottom or lowest point, in contradistinction to jaws which have narrow acute-

angled grooves such as in Patent No. 1,163,145 where sharp edges of these grooves would contact the tubing or convex surface and tend to mar such surface, while being so near the lowest point of the latter that displacement of the material would be likely to occur whenever any adjustment of the material would be attempted.

While recognizing that the differences between this invention and previously patented ones are not great, it is desired to impress the fact that these differences are sufficient to turn difficulty into convenience, time-loss into time-saving, and haphazard into precision.

It is not intended to limit this invention or its patent protection to the exact details herein described or herewith illustrated, for the invention is susceptible of numerous changes within the inventive ideas as implied and claimed.

I claim the following as my invention:

A C-clamp that comprises an integrally formed 20 C-shaped frame having a screw-threaded open-

ing and a cylindrical pivot-bearing in axial alignment with one another, a hand-screw operatively seated in said screw-threaded opening and being provided with a substantially circular jaw having its axis aligned with the axis of said hand-screw and being pivotally engaged with the hand-screw, and a second substantially circular jaw provided with a pivot that is rotatably seated in said pivot-bearing of said frame in axial alignment with the axis of said hand-screw, each one 10 of said jaws having a work-engaging face that comprises at least three ridge-crests that converge substantially from its periphery to its central portion, whereby these jaws are cooperatively related for automatically centering two articulate-surfaced bodies when operated to clamp said two bodies against one another when they are between these jaws, substantially as specified and shown.

ANTHONY A. WASILEWSKI.
